ELECTRIC SWITCH

Frank O. Kuhn, Flint, Mich.

Application November 9, 1936, Serial No. 109,986

4 Claims. (Cl. 200—34)

This invention relates generally to switches for controlling electric circuits and refers more particularly to improvements in switches embodying means for delaying opening the circuit after the switch control has been moved to its "off" position.

It is one of the principal objects of this invention to improve generally switches embodying the above feature by simplifying the construction of the several parts involved and by reducing the number of such parts to a minimum. In accordance with this invention, the construction of the switch is not only materially simplified, but the operation thereof is rendered more efficient by reason of the extremely simple escapement mechanism provided to prevent disengagement of the relatively movable switch contacts upon moving the switch control to its "off" position and to permit the release of the contacts in predetermined timed relation of movement of the switch control to its "off" position.

Another feature of this invention consists in the provision of an escapement mechanism for the above purpose embodying a latch for positively holding the relatively movable switch contacts into engagement and having pneumatically operated means effective upon movement of the switch control to its "off" position to release the contacts in predetermined timed relation to movement of the control to the latter position thereof.

Still another advantageous feature of this invention resides in the provision of escapement mechanism of the character set forth capable of being used in connection with switches embodying a well known and proven principle of operation. In addition, the invention contemplates a switch construction and escapement mechanism forming a unitary assembly compact in nature and capable of being readily installed.

A further object of the present invention consists in the provision of a switch construction embodying the above features which is effectively sealed against the entrance of dirt and moisture and which is durable in construction. This feature, as well as the above and other objects, will be made more apparent as the description proceeds, especially when considered in connection with the accompanying drawings, wherein—

Figure 1 is a central sectional view through the switch assembly and illustrating the several parts thereof in a position wherein the switch control is in its "off" position and the circuit controlling means is latched by the escapement mechanism in the "on" position;

Figure 2 is a plan view of the construction shown in Figure 1, with certain parts broken away for the sake of clearness;

Figure 3 is a sectional view taken substantially on the plane indicated by the line 3—3 of Figure 2;

Figure 4 is a sectional view taken substantially on the plane indicated by the line 4—4 of Figure 2;

Figure 5 is a sectional view taken substantially on the line 5—5 of Figure 2 and illustrating the switch control in its "on" position;

Figure 6 is a cross sectional view taken on the line 6—6 of Figure 4;

Figure 7 is a fragmentary sectional view of a slightly modified form of the invention; and

Figure 8 is a fragmentary perspective view of the switch control means.

In the specific embodiment of the invention selected herein for the purpose of illustration, the invention is shown in connection with a switch operating on the well known toggle principle and comprising a casing 10 formed of molded rubber, Bakelite, or other suitable material and housing circuit controlling means 11 adapted for actuation by a control member 12 pivotally supported on the casing 10 for swinging movement in opposite directions. The circuit controlling means 11 comprises a pair of fixed contacts 13 respectively secured to the inner surfaces of the opposite side walls of the casing by means of the terminals 14 and having flexible fingers 15 extending inwardly from the lower ends thereof for frictional engagement with the cooperating movable contact member 16. The movable contact member 16 is substantially U-shaped in elevation and is provided with laterally outwardly extending projections 17 at the upper extremities of the leg portions thereof. The projections 17 are positioned in suitable slots 19 formed in the opposite side walls of the casing to provide for swinging movement of the cross bar 20 of the U toward and away from the flexible fingers 15 of the cooperating fixed contacts 13. The distance between the flexible fingers 15 is less than the width of the base portion of the U-shaped contact member 16 so that when the latter is swung to position the base portion thereof between the fingers, the latter are tensioned and frictionally engage the opposite sides of the U-shaped member to insure efficient flow of electrical energy through the circuit.

As briefly indicated above, the swinging contact member 16 is moved into and out of engagement with the fixed contact 13 by means of the

control 12. In detail, the control 12 is fixed upon a shaft 21 intermediate the ends of the latter and the opposite side wall portions of the casing are slotted, as at 22, for pivotally supporting the ends 5 of the shaft 21. The operative connection between the control 12 and swinging contact member 16 comprises a coil spring 23 having the lower end positioned on a projection 24 of the cross bar 20 and having the upper end secured to a lever 25 10 permanently secured to the shaft 21. The axis of rocking movement of the switch contact 16 is so positioned with respect to the axis of rocking movement of the switch control shaft 21 that the line of action of the spring 23 alternately assumes positions on opposite sides of the contact member 16 when the control 12 is rocked from one extreme position to the other. In other words, the construction is such that when the control 12 is swung from the "off" position to the 20 "on" position, the upper end or the line of action of the spring moves from the right-hand side (as viewed in Figure 1) of the axis of swinging movement of the contact 16 to the left-hand side of this axis and, as a result, the contact member 16 25 is snapped into engagement with the cooperating fixed contacts 13. On the other hand, when the switch control 12 is swung to its "off" position, the line of action of the spring returns to the right-hand side of the axis of swinging movement 30 of the contact 16 and tends to snap this contact out of engagement with the fixed contacts 15.

In the present instance, provision is made herein for preventing swinging movement of the contact 16 out of engagement with the 35 relatively fixed contacts 15 when the switch control 12 is swung from the "on" position thereof to the "off" position of the same until a predetermined interval of time elapses. This is accomplished herein by escapement mechanism 26 embodying a latch 27 for holding the swinging contact 16 into engagement with the relatively fixed contacts 15 and having pneumatically operated means 28 for releasing the latch from the contact 16 in timed relation to swinging movement of the switch control from its "on" to its "off" position. 40 In detail, the latch 27 comprises an arm 29 pivotally supported within the casing on one side wall thereof and having a notch 30 in the swinging end thereof adapted to receive a projection 31, extending laterally from the movable contact 16, when the latter is swung to its operative position, shown in Figure 1. It will be observed from this latter figure that the latch arm 29 is normally urged into frictional engagement with the projection 31 on the contact 16 by means of a suitable spring 32, with the result that when the switch contact 16 is swung to its operative position, shown in Figure 1, the notch 30 in the free end of the arm 29 snaps into engagement with the projection and prevents disengagement of the contact 16 with the contacts 13 by the spring 23 when the latter is moved to its "off" position by the switch control 12.

The pneumatic means for releasing the latch arm 29 from engagement with the projection 31 in timed relation to movement of the switch control 12 from its "on" position to its "off" position is shown in Figure 1 as having a sealed air chamber 33 formed by the co-operation of a flexible 65 diaphragm 34 with a recess 35 in the inner side of a cap 36 removably secured to the rear end of the casing 10 by means of the fastener elements 37. The peripheral edges of the diaphragm 34 are effectively clamped between the cap 36 and an annular sealing gasket 38 clamped against the 70

underside of the casing 10 by the fastener elements 37. A pair of plates 39 are clamped to opposite sides of the central portion of the diaphragm 34 and these plates, as well as the diaphragm, are formed with aligned openings there-through for receiving a fixture 40. The fixture 40 is provided with a head portion 41 engaging the inner side of the innermost plate 39 and the lower end of the fixture is spun over the plate 39 at the outer side of the diaphragm to effectively 10 clamp the latter therebetween. Upon reference to Figure 1, it will be noted that the central portion of the fixture is apertured, as at 42, to establish communication between the chamber 33 and atmosphere. An annular valve seat 43 is formed 15 on the inner surface of the fixture 41 around the opening 42 and the latter is normally closed by a spring loaded valve disc 44 engaging the seat 43.

In the present instance, air is exhausted from the chamber 33 through the passage 42 in the 20 fixture 41 when the switch control 12 is moved from its "off" position to its "on" position. This is accomplished herein by providing a cam 45 on the switch control shaft 21 adapted to engage the extremity of an inwardly extending projection 25 46 on the innermost plate 39 to force the projection 46 outwardly when the control 12 is swung to its "on" position. Outward movement of the projection 46 reduces the volume of the chamber 33 by displacing the central portion of the diaphragm 34 into the chamber and the consequent pressure built up in the chamber 33 opens the valve 44, permitting the fluid or air in the chamber to escape into the atmosphere. On the other hand, when the cam 45 is moved by the control 12 35 to its "off" position, the spring 50 is free to act on the central portion of the diaphragm 34, tending to move the latter and projection 46 inwardly. The rate at which the spring moves the projection 46 inwardly is dependent upon the return of flow of the fluid or air back into the chamber 33 40 and this return flow of fluid is controlled by a highly restricted vent 48 formed in the fixture 41 adjacent the passage 42. For the purpose of regulating the speed of travel of the projection 45 46, an adjustable valve member 49 is threaded in the restricted vent 48 and functions to vary the cross sectional area of this vent.

As the projection 46 approaches its inward-most position, the latch arm 29 is released from the projection 31 on the contact member 16 and the spring 23 disengages the contact member 16 50 from the relatively fixed contacts 15 in the usual manner. For accomplishing this result, the projection 46 is provided with a shoulder 51 adapted to engage a lateral projection 52 on the arm 29 to lift the latter a sufficient distance to disengage the free end of the same from the contact member 16.

It will be noted from Figure 2 of the drawings 55 that the projection 46 operates in an extension 53 of the casing 10 and a gasket 54 is secured in the extension for frictionally engaging the projection to provide a seal around the latter sufficient to prevent the entrance of dirt and moisture into 65 the chamber of the casing containing the valves for the pneumatic means. As a result, the switch will operate efficiently over a long period of time and the cost of maintenance is reduced to the minimum.

The embodiment of the invention illustrated in Figure 7 differs from the one previously described in that the marginal portions of central opening in the innermost plate 60 extend through the aligned openings in the outermost plate 61 70 75

and are crimped over the marginal edges of this opening to provide a unitary construction. Also in this embodiment, an elastic valve member 62, preferably of molded rubber, is substituted for the fixture 40 in the first described form of the invention and is secured to the plates in the aligned openings thereof by means of lugs 63 at the outer end of the valve. It will be observed from Figure 7 that the valve member 62 is provided with a passage therethrough containing a plug 64 of porous material. With this construction, air is forcibly discharged from the chamber past the elastic check valve 62 by the projection 46 when the latter is moved outwardly by the switch control member and will be permitted to filter back into the chamber through the porous plug when the cam on the switch control member is in its released position. With the above exceptions, the modified construction operates in a manner identical to the embodiment previously described.

What I claim as my invention is:

1. In a device of the character described, a movable element, a movable operating member, resilient means interconnecting said member and element, whereby movement of said operating member tends to cause movement of said element, a latch engaging said element, an expandable sealed chamber, means normally biasing said chamber to expanded position, valve means for said chamber providing for timed expansion of said chamber under control of said biasing means, a part engaging said chamber and engageable by said member, the aforesaid movement of said member disengaging said member from said part to permit timed expansion of said chamber, and means on said part engaging said latch to free same from said element.
2. In a device of the character described, a movable element, a movable operating member, resilient means interconnecting said member and element, whereby movement of said operating member tends to cause movement of said element, a latch engaging said element, an expandable sealed chamber having a flexible wall, an aperture in said wall, an annular plate doubled around said aperture, means normally biasing said chamber to expanded position, valve means for said chamber carried by said plate and providing for timed expansion of said chamber under

control of said biasing means, a part engaging said chamber and engageable by said member, the aforesaid movement of said member disengaging said member from said part to permit timed expansion of said chamber, and means on said part engaging said latch to free same from said element.

3. In a device of the character described, an element movable to two positions, an operating member movable to two positions, resilient means interconnecting said member and element whereby movement of said member to one position biases said element to a corresponding position, a latch retaining said element in one position, an expandable chamber having a fixed and a movable wall, a latch releasing part carried by said movable wall, means urging said wall in a direction to cause said latch releasing means to release said latch, said operating member operatively associated with said latch releasing part and effective when said member is in position to bias said element toward latched position to move and retain said movable wall against its urging means, and effective when said operating member is in position to bias said element away from latched position to release said movable wall for motion by its urging means, a one-way valve in said chamber permitting ready movement of said movable wall against its urging means, and said chamber having an orifice controlling movement of said wall in the opposite direction.

4. In a device of the character described, an expandable chamber having a fixed and a movable wall, means urging said movable wall in one direction, a one-way valve adapted to be closed by the pressure difference caused by motion of said wall in said direction, said chamber having a metering orifice providing timed motion of said wall in said direction, a snap acting setting and releasing mechanism comprising a two position member, resilient means urging said member to either limiting position, a connection between said member and said movable wall adapted to move and retain said wall against its urging means when said member is snapped to one position, and to release said wall for timed motion when said member is snapped to the other position.

FRANK O. KUHN. 50
